(57) CLAIM

The ornamental design for a diaper bag, as shown and described.

DESCRIPTION

A portion of the disclosure of this patent document contains material which is subject to copyright protection. This patent document may show and/or describe matter which is or may become trade dress of Maelstrom. The copyright and trade dress Maelstrom has no objection to the facsimile reproduction by anyone of the patent disclosure as it appears in the Patent and Trademark Office patent files or records, but otherwise reserves all copyright and trade dress rights whatsoever.

FIG. 1 is a front perspective view of a diaper bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a exploded view of FIG. 1;

FIG. 10 is an enlarged view of the area labeled 10 in FIG. 1;

FIG. 11 is an enlarged view of the area labeled 11 in FIG. 1;

FIG. 12 is an enlarged view of the area labeled 12 in FIG. 1;

FIG. 13 is an enlarged view of the area labeled 13 in FIG. 1;

FIG. 14 is an enlarged view of the area labeled 14 in FIG. 1;

FIG. 15 is an enlarged view of the area labeled 15 in FIG. 2;

FIG. 16 is an enlarged view of the area labeled 16 in FIG. 2; and,

FIG. 17 is an enlarged view of the area labeled 17 in FIG. 2.

The broken lines in the drawings illustrate the portions of the diaper bag, which form no part of the claimed design.
